UNITED STATES PATENT OFFICE.

JOSEPH ELDER, OF PEORIA, ILLINOIS.

SYSTEM OF HEATING RAILWAY-CARS.

SPECIFICATION forming part of Letters Patent No. 415,907, dated November 26, 1889.

Application filed July 15, 1887. Serial No. 244,410. (No model.) Patented in Canada June 22, 1887, No. 27,017.

To all whom it may concern:

Be it known that I, JOSEPH ELDER, of Peoria, in the county of Peoria and State of Illinois, have invented certain Improvements 5 in Systems of Heating Railway-Cars, (patented in Canada June 22, 1887, No. 27,017,) of which the following is a specification.

The aim of my invention is to provide a practical system and apparatus for the heating 10 of railway-cars, by which the cars may be uniformly and fully heated in all parts, and which shall be adapted to meet the varying conditions and requirements encountered in practice.

15 To this end it consists in providing the cars with hot-water-circulating pipes and valves, and couplings for making connections for said pipes, and in providing at the station boilers for heating the water, with suitable 20 valves and couplings for connecting temporarily with the cars; and also in providing at the station the tank or receptacle with suitable pipes and connections for receiving the partially-cooled water from the cars, with 25 means for returning the same to the boiler or heater, and also in various other details, which will hereinafter appear.

In the accompanying drawings, Figure 1 is 30 an elevation, partly in section, showing a railway-station with the proper heating and receiving apparatus and their connections, and two railway-cars connected with said apparatus to receive a supply of heated water and deliver the previous supply of partially-cooled water. Fig. 2 is a top plan view illustrating the arrangement of the heating-pipes within the car. Fig. 3 is a vertical cross-section of the car on the line 1 1 of Fig. 1. Fig. 4 is a vertical cross-section on the line 2 2 of Fig. 5, on a larger scale. Fig. 5 is a horizontal section on the line 4 4 of Fig. 3, showing the arrangement of the registers with reference to the seats and aisles. Fig. 6 is a cross-section on the line 5 5, Fig. 1, showing the 45 construction of the pipe-coupling. Fig. 7 is a side elevation showing the same parts. Fig. 8 is a sectional elevation on the line 6 6, Fig. 2, showing the supplemental heater. Fig. 9 is a diagrammatic view showing the connections between the valves.

In carrying my invention into effect I lo-

cate at each of the terminals and at suitable intermediate stations on the line a steam-boiler A, which may be of any ordinary or appropriate form adapted to heat water or other appropriate fluid to a high temperature. Adjacent to this boiler I locate a tank or receiver B, designed to receive the cooled or partially-cooled water from the cars. This reservoir I connect with the boiler by a pipe 55 60 C or equivalent connection, provided with a steam-pump, an injector, or equivalent apparatus D, by which the water may be delivered from the reservoir as required.

From the boiler, at a point beneath the 65 water-line, I extend one or more pipes E along the tracks of the railway, preferably a distance equal to the length of the longest passenger-trains, and at suitable intervals I provide this pipe with branch pipes E', each 70 provided with a closing-valve E² and with a flexible section E³, terminating in a coupling E⁴, adapted for connection with the pipes of the cars, as hereinafter explained.

From the tank or reservoir B, I extend a 75 pipe F along or adjacent to the track, and provide it at suitable intervals with a series of branches F', terminating at the top in an enlarged funnel or receiving-mouth F², or otherwise formed to receive the water delivered 80 from the cars.

It will be understood that there is at each station a series of delivery branches E' and of the receiving branches F', so that connections may be made directly and separately 85 with each car in the train to deliver the heated water thereto and the cooler water therefrom.

The cars, which may be in all other respects of the usual construction, I provide 90 immediately beneath the ordinary floor with a system of horizontal circulating-pipes G, extending longitudinally and transversely, forming a complete net-work throughout its entire area. Except at the upper side, where 95 they are left uncovered, the pipes are bedded, as shown in Fig. 4, in non-conducting material a—such as asbestos or mineral wool—supported in an inclosing box or housing b.

At each end of the car I carry the pipes upward over the top of the door from one side to the other, as shown at c, Fig. 3, in order to 100

form a stand-pipe containing a supply of fluid, by which the pipes are kept completely full at all times. I commonly provide this stand-pipe with a small air vent or opening *d* at 5 the top.

I provide in the car-floor a series of registers *e*, located directly over the steam-pipes and arranged in irregular or zigzag line, as shown in Fig. 5, being located alternately 10 near the aisle and near the outside of the car, as plainly shown, it being found in practice that this arrangement affords a more uniform and equal distribution of the heat than is otherwise obtainable. At each end of the 15 car the pipes are extended on both sides to the outside, provided with closing valves or cocks *H*, and also with coupling-necks *I*, adapted to receive the station-coupling *E*⁴ already referred to.

20 At a suitable point in the length of the car, preferably near one corner, I locate beneath the floor a supplemental heater *J*, consisting simply of a fire pot or box with an ordinary grate, through the upper part of which one 25 of the pipes *G* is extended. This heater is called into action only on exceptional occasions, as hereinafter explained.

In order that the station-pipes *E*³ may be quickly connected to and disconnected from 30 the pipes of the car, I recommend the construction of details such as represented in Figs. 6 and 7. The radiating-pipe *G* of the car is provided near each end with an inwardly-opening check-valve *K*, held normally 35 in a closed position by a spiral spring *h* or provided with a closing-valve of any other approved form. The spindle of each valve is extended outward through the stuffing box or gland and connected to an angular lever 40 *i*. Each of these levers is pivoted to the car and has its opposite end pivoted to a rod *k*, extending lengthwise of the car, as shown in Fig. 9. One end of this rod extends beyond the angular lever, where it terminates in a 45 forked end having flanges *K'*, the purpose of which will presently appear.

The coupling on the end of the station branch *E* is provided with the usual rotary sleeve having threads or lips to engage corresponding lips on the end of the car-pipe, as 50 in other pipe-couplings now in general use. I provide this coupling-sleeve with two arms *m*, formed and arranged in such manner that when the coupling is applied to the end of 55 the car-pipe and turned to fix it in position thereon the arms *m* will encounter the flanges *K'* and will operate the rod *k* and through the intermediate parts open the valve at the opposite end of the pipe on the car. It will 60 be perceived that in this manner the connection of the supply-pipe at one end of the car is caused to effect the opening of the discharge-valve at the opposite end, in order that the water which is contained in the pipes of 65 the car and the temperature of which has been lowered by radiation may escape through the outlet-valve and make room for the in-

flowing highly-heated water by which it is driven out.

The essence of my invention as regards the 70 valve mechanism consists in connecting the coupling at one end through intermediate devices with the outlet-valve at the opposite end, and it is manifest that the details may be modified in various respects which will 75 suggest themselves to the skilled mechanic without passing beyond the limits of my invention.

As the changing temperature of the water within the car may require a regulation of the 80 registers in order to maintain a practically uniform temperature of the air, I connect the registers throughout the car in such manner that they may be all operated and controlled 85 from one end by the conductor or other attendants.

As shown in the drawings, the registers are of the familiar type in which a series of pivoted slats are mounted in a frame and controlled by a rock shaft or spindle. I provide 90 these spindles at their inner ends with cranks *o* and connect these cranks to rods *p*, extending lengthwise of the car, as shown in Fig. 5, so that the movement of either rod will adjust the entire series of registers on that side 95 of the car.

In operating my system the boiler is charged with water and the fire regulated in such manner as to bring the water to a high temperature and maintain a reasonable pressure of 100 steam within the boiler. When an incoming train reaches the station, the cars are brought with their ends adjacent to the pipes *E*³ and *F'*. Each of the branches *E*³ is connected by 105 its coupling *E*⁴ to the circulating or radiating pipe at one end of the adjacent car. The application of the coupling not only connects the pipe *E*³ to the pipe of the car, but at the same time opens the car-pipe at the opposite end, as before explained. The valve *E*² in 110 each branch pipe is now opened, whereupon the pressure of the steam in the boiler drives the water forcibly through the pipe *E* and through its branches into the car-pipes. The hot water entering the pipes at one end displaces the cooler water therein and drives 115 the same forcibly out of the same at the opposite end, where it is discharged into the branch pipes *F'* and returned through pipe *F* into the reservoir *B*. The pipes being thus 120 charged with hot water, the valves *E*² are closed and the branch pipes *E*³ uncoupled, the effect of which is to close the valves of the car, and thus retain the hot water therein. The water delivered from the car is commonly 125 at a temperature but little below the boiling-point, and in this condition it is returned by the pump *D* to the boiler, the expenditure of fuel being thus economized.

It will be observed that by the use of a long 130 supply-pipe *E*, having a series of branches which may be connected simultaneously to separate cars, I am enabled to fill a large number of cars at the same time, each independ-

ently of the other, and thus to prevent any undue detention of the train at the station.

If for any reason the temperature of the water in the pipes should become unduly diminished between stations, or if the car should be detained at stations which are unprovided with means for hot-water supply, it is only necessary to build a fire in the supplemental furnace or heater J, by which the water in the pipes may be raised to any required temperature.

Having thus described my invention, what I claim is—

1. In combination with a railway-train having each of its cars provided with a coil of water-circulating pipes having terminal couplings and valves by means of which the said coil may be filled and emptied at will, a steam-boiler located at a station and provided below the water-line with a discharge-pipe having branches each with a coupling and valve adapted for connection with the coil of the car, and a receiving-tank, also located at a station and provided with a pipe adapted to receive the water discharged from the cars, whereby the heating-coils in all the cars of a train can at one and the same moment receive the hot water from the boiler and eject the cooled water into the receiving-tank, substantially as set forth.

2. In combination with a railway-car provided with water-circulating pipes and with valves for closing the ends of said pipes, a

stationary water-supply pipe, a coupling for connecting the same with the car-pipe, and 35 automatic lever-connections interposed between the coupling and the outlet-valve of the car-pipe, whereby the application of the said coupling at one end of the car-pipe will cause the opening of the valve at the other end of 40 the same, substantially as shown, and for the purpose set forth.

3. In a railway-car, the water-circulating pipes having valves K at opposite ends, in combination with lever i, pivoted to the car, 45 and rod k, connected therewith, substantially as shown and described, and for the purpose set forth.

4. In a system for heating railway-cars, the stationary steam-boiler provided with a delivery-pipe having branches with terminal coupling and valve for each branch, in combination with a series of cars, each having a coil of heating-pipes and a branch pipe with terminal coupling and valve to correspond 50 with each delivery-pipe branch, whereby hot water may be delivered at will into the cars simultaneously, the delivery to each car being effected and controlled independently.

In testimony whereof I hereunto set my hand, this 22d day of April, 1887, in the presence of two attesting witnesses.

JOSEPH ELDER.
